L.W.Tilton

By *A. H. Andrews Jr.* Attorney

UNITED STATES PATENT OFFICE.

LEWIS W. TILTON, OF MIAMI, FLORIDA.

BUILDING FORM.

Application filed December 2, 1920. Serial No. 427,750.

To all whom it may concern:

Be it known that I, LEWIS W. TILTON, a citizen of the United States, residing at Miami, in the county of Dade and State of Florida, have invented certain new and useful Improvements in a Building Form; and I do hereby declare the following to be a full, clear, and exact description of the invention, such as will enable others skilled in the art to which it appertains to make and use the same.

The object of the invention is to provide a simple, relatively inexpensive and efficient filling unit for building forms as a substitute for the wooden fillers ordinarily employed between the joist and girders in concrete and similar work in connection with building operations, and more especially to provide a unit which can be used repeatedly and for an indefinite length of time and is adaptable to the varying joist spacing to be found in buildings and which are usually arranged on twelve inch, fourteen inch or sixteen inch centers according to the purposes for which the buildings are designed; and with this object in view the invention consists in a construction and combination of parts of which a preferred embodiment is shown in the drawing, where

Figure 1 is a plan view of a filler unit embodying the invention arranged in the operative position with relation to the building timbers.

Figure 2 is a detail view of the unit detached, and showing in dotted lines the adjusted position of the supporting bracket by which the same is adapted for use in connection with joists spaced at the intermediate interval of, say, fourteen inches.

Figure 3 is a view similar to Figure 1, illustrating the manner in which the filler unit is used in connection with joists spaced at an intermediate interval.

Figure 4 is a fragmentary plan view showing the invention in use.

The device consists essentially of metal plate 10, preferably sheet metal as steel to which is attached means for supporting the same in proper position with relation to the joists 11 or other timbers of the building structure, said means in the construction illustrated consisting of angular brackets 12, one arm of which is secured by bolts 13 to the plate while the other arm is provided with perforations 13' through which nails 14 may be driven to attach the brackets to the

timbers such as flooring 15, permanent or temporary, it being preferable to drive these nails, as shown, only a part of the way and then bend them over so that they may readily be withdrawn when the unit is to be displaced at the completion of the operation.

Figure 4 best illustrates the use of the plate 10. A concrete or equivalent wall is suggested at 16 having the ends of joists 11 extending into the same. This wall is poured between an outside form 17 and an inside form 18 and it is customary to nail boards in the intervals between the joists 11, the form 18 and the timbers 15. The plate 10 is used instead of said boards in accordance with my invention. As the joists 11 are variously spaced in accordance with building rules or customs either at twelve, fourteen or sixteen inch centers, the plate consists of a main plate or body portion 10^a having a width and a length adapted respectively for the intervals between joists spaced at twelve and fourteen inches between centers and an extension 10^b serving to add to the width of the plate to adapt it to fill the interval between joists spaced at sixteen inch centers. The extension member is secured to the body member by means of bolts 13 engaging registering openings in the members and serving to permit of the detachment of the extension with facility when the device is to be used in connection with joists spaced at twelve inch centers. To convert the unit arranged for use either in connection with joists spaced at twelve or sixteen inch centers, to adapt it to be used in connection with joists spaced at fourteen inch centers or at the intermediate dimension, it is only necessary to shift the supporting bracket from the side edge to the end edge of the body member of the plate, to use the supplemental bolt holes 14, such adjustment or rearrangement being indicated in dotted lines in Figure 2, and obviously being such as can be effected by cheap labor and without necessitating expert or skilled workmen.

Thus by providing a plate of which the body portion is of oblong form adapting its width and length respectively to the intervals represented by different spacings of the building joists or timbers, and providing the plate with an extension in one direction, it is possible to adapt the plate to the several spacings of joists and other like floor timbers as they are ordinarily arranged, or as they are universally arranged in connection

with the customary rules of building construction. The interchangeability of the supporting means to adapt the same to either the side or end edges of the body member of the plate, or other perpendicularly disposed edges thereof, the said body member of the oblong form indicated, enables the unit to be properly supported during the operation of placing the concrete or cement and at the same time facilitate the removal thereof after the completion of the operation. To hold the bottom the unit should be dropped from the inside of the girders so that the bracket will rest on the sub-floor over the girders whereupon nails may be driven in the openings or perforations in the perpendicularly disposed bracket arms to hold the device in place. The opening 16 at the center of the plate is provided for a wire to be used in connection with foundations when the same are poured.

Having thus described the invention, what I claim is:

1. A filler unit for building forms having a plate of greater length than width, an extension attachable to the plate to increase the width thereof, whereby the unit may be used between joists spaced at different distances apart.
2. A filler unit for building forms having a plate of greater length than width and means to selectively support the plate with

a side or end uppermost whereby the unit may be used between joists spaced at different distances apart.

3. A filler unit for building forms having a plate, and supporting means for interchangeable connection adjacent to one edge of said plate and adjacent to another edge of said plate at an angle to the first mentioned edge.

4. A filler unit for building forms having an oblong plate, angular supporting brackets and bolts for securing the plate to said brackets, said plate being provided with bolt openings in operative relation with perpendicularly disposed edges thereof.

5. A filler unit for building forms having a plate consisting of a body member and a detachable extension member, said body member being of oblong form, supporting brackets and means for attaching the supporting brackets to the body member of the plate and adapted for interchangeably arranging the brackets adjacent to a side or end edge of said body member.

In testimony whereof I affix my signature in presence of two witnesses.

LEWIS W. TILTON.
